UNITED STATES PATENT OFFICE.

DAVID H. STROUD, OF PHILADELPHIA, PENNSYLVANIA.

DESIGN FOR A TABLE-COVER.

SPECIFICATION forming part of Design No. 24,808, dated October 29, 1895.

Application filed September 7, 1895. Serial No. 561,868. Term of patent 3½ years.

To all whom it may concern:

Be it known that I, DAVID H. STROUD, a citizen of the United States, residing at Philadelphia, in the county of Philadelphia, State 5 of Pennsylvania, have invented certain new and useful Improvements in a Design for Table-Covers, Rugs, Carpets, &c.; and I do hereby declare the following to be a full, clear, and exact description of the invention, such 10 as will enable others skilled in the art to which it appertains to make and use the same.

My invention relates to a design to be worked into or upon table-covers and similar articles; and I do hereby declare that the accompanying drawing and specification give 15 and convey to any person skilled in the art of fabric-weaving a sufficiently clear understanding of the same to enable such person to use my invention.

20 The drawing is a face view of a table-cover embodying my invention, the figure illustrating a panel and three sides of a border, the fourth side being identical with those shown.

The essential feature of my invention is the central panel A, characterized by a group of 25 horses and their respective jockeys finishing a race, the grand stand and judges' stand being shown in the rear, the whole being gradually shaded off to a border B, which is characterized by a number of curves inclosing 30 conventionalized flower forms.

The colors employed for the different portions of this design may be varied to suit the taste or convenience of the manufacturer.

What I claim, and desire to secure by Letters Patent, is—

The design for a table-cover, substantially as shown.

In testimony whereof I affix my signature in presence of two witnesses.

DAVID H. STROUD.
